SNOWPLOW

Frederick James Roth, Hucknall, England

Application May 17, 1943, Serial No. 487,361
In Great Britain April 9, 1942

1 Claim. (Cl. 37—42)

The invention is concerned with a snowplow, and its principal object is the provision of a snowplow capable of a double function, viz., the removal of deep snow and the subsequent removal of compacted snow and ice by means of a planing action. For this purpose a snowplow according to this invention is provided with skids for the support of the mould board or blade, and with adjustment means for effecting a relative height adjustment as between the lower edge of the blade and the skids, whereby the relation between said lower edge and the ground surface may be varied. Thus with the lower edge of the blade raised just above the ground surface or road surface, deep snow may be plowed away. Alternatively, by making the appropriate adjustment the front edge of the blade may be lowered on to the road surface so that compacted snow and ice may be planed away. The adjustment is preferably a spring adjustment and to this end may include compression springs so disposed that adjustment tending to lower the said edge is effected against the spring action.

The foregoing and other features of the invention set out in the appended claim is incorporated in the construction now to be described, as a preferred example of the invention, with reference to the accompanying drawings, in which

Figure 1 is a plan view of the plow;

Figure 2 is a section on the line 2—2 of Fig. 1 and illustrates the attachment of the plow to a propelling motor vehicle; and

Figure 3 is a sectional elevation, on a larger scale, taken on the line 3—3 in Fig. 1.

Figure 4 is a plan view of a modified construction of plow;

Figure 5 is a side elevation thereof;

Figure 6 is a longitudinal section, on a large scale, showing a detail thereof; while

Figure 7 is a further longitudinal section showing one of the skids.

In the illustrated construction according to this invention, Figs. 1-3, the plow is designed to be propelled by a motor vehicle 10 and consists of a framework 11 pivotally attached at its rear end, at 12, to the chassis of the vehicle and having a blade 13 wider than the frame, obliquely disposed to the length of the vehicle at its front end, the said blade 13 normally occupying a vertical plane and having its upper edge 13' curved forward. The frame 11 is provided at each side and at the immediate rear of the blade 13 with a skid 14. Each skid consists of a metal plate bent to curve downwards between its front and rear ends. These ends are transfixied by bolts 15 which ex-

tend upwards through suitable holes in the plow frame and at their top ends, above the frame, are provided with nuts 16 from which radiating arms extend so that they may readily be turned by hand. Additionally a strong compression spring 17 encircles each bolt between the skid 14 and the underside of the frame 11. Therefore, by screwing the nuts 16 down the bolts 15 the springs 17 are compressed and the skids 14 are drawn closer to the frame 11 so that the blade 13 is lowered. Alternatively, if the nuts 16 are slackened off the springs 17 expand and the blade 13 is raised. In order to relieve the bolts 15 of the rearward thrust necessarily imparted to the skids 14 as they run on the surface of the ground or snow, a thrust plate 18 is provided at each side of the plow frame against which plate 18 an upturned portion 14' of the rear end of the adjacent skid 14 bears.

20 The frame 11 consists of two longitudinal members 11a connected by transverse members 11b at least at the front and at the rear and preferably also at an intermediate location a short distance from the front end, the said longitudinal members 11a being braced together by diagonal members 11c. At the rear each frame member 11a is provided with an upstanding plate or bracket 19 pierced with a hole through which, and through a similar hole in a plate

25 20 attached to the adjacent chassis member 21 of the vehicle 10, a pivot bolt or pin 12 may be inserted. The frame 11 is therefore pivotally suspended at its rear end and at its front end the weight is carried by the skids 14 or by the lower edge of the blade 13. Towards the front, and preferably adjacent to the intermediate transverse member 11b, two angle iron (or channel) uprights 22 are provided. These engage between two forwardly projecting brackets

30 35 40 45 50 23 which are secured to the front end of the longitudinal chassis members 21 of the vehicle and prevent lateral play of the frame 11. The uprights 22 are pierced at suitable locations in their height with holes 24 through which, and through holes in the aforesaid side brackets 23, pins may be inserted so that the frame may be secured in any one of several raised positions, as for example in a raised inoperative position when the plow is being moved from one location to another. The side members 23 may be connected by a cross member 25.

The plow blade 13 is pivoted to the front end of the frame 11 about an axis 26' (which is oblique to the direction of travel but extends longitudinally of the blade) so that should its

lower edge meet an obstruction (e. g. a manhole cover) the said lower edge may yield backwardly and the top edge may swing forward. This yielding movement is opposed by tension springs 27 extending between the plow blade near the upper edge thereof and the frame. In its normal operative attitude the plow blade is drawn by said springs 27 backwards against two or more stops 28 which are conveniently formed by right-angled brackets fixed vertically at the front ends of the frame members 11a.

It is also preferable to provide means for adjusting the initial height of the blade 13 on the frame 11. For this purpose, at the rear face of the blade there is a plurality of uprights 30 each conveniently consisting of a length of angle iron pierced with holes 31 at a plurality of locations one above the other, through any of which holes 31 and through holes in suitable members 32 at the front end of the frame, horizontal pivot bolts or pins 26 may be inserted. Conveniently the blade is pivoted at three locations in its width, that is to say at the front end of each longitudinal member 11a of the frame and at a location which is spaced laterally from the frame at the rearward end of the oblique blade. The pivot at this last mentioned location may be carried by a member 11d extending diagonally forward from the adjacent side member of the frame.

The lower edge of the blade 13 may be provided with a renewable metal strip 13a.

In the modified construction shown in Figs. 4-7, the skids 114 are located within the width of the frame members 111a and are preferably shod with renewable wearing shoes or wearing plates 114b of hard-wearing metal. They are guided at their front and rear ends in channel-like guide members 118. The plow is pivotally suspended at its rear end by means of upstanding brackets 119 riveted or bolted to each frame member 111a. A plate 133 bolted to each adjacent chassis member 121 depends downwardly and each associated bracket 119 and plate 133 is transfixied by a bolt or pivot pin 112 about which the plow

5 pivots. A series of holes 134 in the plates 133 allow of vertical adjustment, and a series of holes 135 on the frame member 111a permits of horizontal adjustment. Lateral movement is prevented by the means more particularly illustrated in Figs. 4-6. On the front axle 136 of the vehicle there is a forward projection 137 formed by parallel vertical angle irons stiffened by webs 137', which projection engages between members 138 projecting rearwardly from a cross member 111b of the plow frame and forming a guide. Means for carrying the plow in a raised inoperative position is provided by bars 139, slideable through guides 140, the rear ends of which bars 139 rest on a part of the vehicle, preferably the front axle 136, and are chamfered as shown at 129' in Fig. 6 to provide a ramp or incline engaging said part or axle. Handles 141 are provided for moving said adjustment bars 139, and they are locked in the adjusted position by dowel pins 142 inserted through selected holes 143 in the bars 139 and registering holes in members 144 on the plow frame. The bars 139 may be adjusted sideways by means of a plurality of bolt holes 145 in the plow frame cross members 111b. The tension springs 127 may be adjusted by turn-buckles 146.

10 Any or all of these features described with reference to Figs. 4-7 may be incorporated in the plow shown in Figs. 1-3 and vice-versa.

I claim:

15 A snowplow having a frame provided with skids for the support of the mould blade, bolts extending upwards from the skids through parts on the frame, nuts on said bolts above said parts, and compression springs encircling the bolts between said parts and skids whereby adjustment tending to lower the edge of the blade relative to the skids is effected against the compression of said springs; and thrust plates carried by the frame engageable by the ends of the skids to relieve the strain on said bolts.

FREDERICK JAMES ROTH.
